UNITED STATES PATENT OFFICE.

MICHAEL JOHN FITZGERALD, OF LOS ANGELES, CALIFORNIA.

FIRE-ESCAPE.

1,117,018.

Specification of Letters Patent. Patented Nov. 10, 1914.

Application filed December 28, 1912. Serial No. 739,057.

To all whom it may concern:

Be it known that I, MICHAEL J. FITZGERALD, a citizen of the United States, and a resident of Los Angeles, in the county of 5 Los Angeles and State of California, have invented a new and Improved Fire-Escape, of which the following is a full, clear, and exact description.

My invention relates to fire escape balconies and ladders, and particularly to a 10 ladder normally supported above the first balcony and adapted to be lowered to the street in an emergency. I provide guides on the first and second balconies in which the 15 ladder has movement, and a novel device on one balcony which will hold the ladder in the raised position above the first balcony, said device being readily movable to release the ladder and permit it to be lowered.

20 The invention will be particularly explained in the specific description herein-after to be given.

Reference is to be had to the accompanying drawings forming a part of this specification, in which similar characters of reference indicate corresponding parts in all the 25 views.

Figure 1 is a front elevation of the fire escape ladder and balconies having my invention applied thereto; Fig. 2 is a sectional plan view on an enlarged scale, the section being taken on the line 2—2 of Fig. 1; and Fig. 3 is a detail transverse vertical section on the line 3—3 of Fig. 2.

35 The ladder A may be of any approved form, comprising side rails, and rungs.

The letter B indicates the second fire escape balcony of a building, and the letter C the first balcony. To the respective balconies guides 10 are secured, and extend outwardly parallel with each other, and are spaced apart to receive the ladder A between them. The guides are formed with T-shaped recesses 11, in which the side rails of the ladder move the rungs extending between the guides 10 and through the contracted openings 12 of the T-shaped recesses. To the rails c, or other portion of the balcony, a bar 14 is pivoted, as at 13, and at a point be-

tween the pivot and the free end of the said 50 bar, which free end constitutes a handle, the bar is given such a formation as to provide a lateral extension to extend beneath the ladder rung and sustain the ladder. In the form shown, the bar 14 is formed with a U-bend 15 in an outer direction immediately adjacent to the pivot 13, such U-bend constituting the lateral extension and the ladder-engaging member. It will be observed from Fig. 2, that the bar 14 may be swung to extend longitudinally of the balcony, with the member 15 extending beneath a ladder rung a. Thus the ladder may be raised from the ground to extend between the first and second balconies, as shown in Fig. 1, and will 60 thus be sustained in position when there is no occasion for the occupants of the building to descend from the first balcony to the street. In case of fire, however, the bar 14 may be swung on its pivot to withdraw the 65 member 15 from beneath the adjacent ladder rung to permit the ladder to drop, the ladder having movement in the guides 10 on the two balconies. The length of the ladder is such that when dropped it will 70 still be held in the guides of the lower balcony C, and firmly sustained in position to enable the occupants of the building to descend with perfect security.

75 The described construction affords a practical means for carrying my invention into effect, but I would state in conclusion, that I do not limit myself strictly to the mechanical details herein illustrated, since manifestly the same can be considerably varied 80 without departure from the spirit of the invention.

Having thus described my invention, I claim as new, and desire to secure by Letters Patent:

90 The combination with a ladder-supporting means, of spaced members forming a guideway adapted to receive a ladder for vertical sliding movement, and a ladder stop consisting of a bar pivoted at one end on the 95 support adjacent to the guideway to swing in a plane transversely to said guideway, said bar having a lateral U-bend at the piv-

oted end, forming a stop projecting at one side, the bar extending from the said bend in the form of an elongated handle and being adapted to swing in an arc in the horizontal plane to bring the lateral bend into or out of the plane of the guideway, to engage or disengage the ladder.

In testimony whereof I have signed my name to this specification in the presence of two subscribing witnesses.

MICHAEL JOHN FITZGERALD.
